UNITED STATES PATENT OFFICE

JAMES W. JENNINGS, OF PROVIDENCE, RHODE ISLAND, ASSIGNOR TO QUAKER SILVER COMPANY, OF ATTLEBORO, MASSACHUSETTS, A CORPORATION OF MASSACHUSETTS

DESIGN FOR A LIGHTER

Application filed September 13, 1930. Serial No. 36,957. Term of patent 7 years.

To all whom it may concern:

Be it known that I, JAMES W. JENNINGS, a citizen of the United States of America, residing at 169 Calla Street, in the city of Providence, county of Providence, and State of Rhode Island, have invented a new, original, and ornamental Design for Lighters, of which the following is a specification, reference being had to the accompanying drawing, forming a part thereof.

In said drawing:

Fig. 1 is a plan view of a lighter showing my new design; and

Fig. 2 is a front elevation thereof.

I claim:

The ornamental design for a lighter substantially as shown.

Signed by me at Attleboro, in the county of Bristol and Commonwealth of Massachusetts, this 8th day of September, 1930.

JAMES W. JENNINGS.
